PICKPROOF LOCK

May Segal, New York, N. Y.

Application November 30, 1946, Serial No. 713,238

11 Claims. (Cl. 70—419)

1

This invention is a novel and improved pick-proof cylinder lock and the objects, advantages and functional and structural features thereof will be more particularly pointed out in the following detailed specification viewed in the light of the accompanying drawings wherein:

Fig. 1 is a longitudinal sectional view of the pickproof cylinder lock according to my invention illustrating the slidably guided accessible knob or closure elevated to permit insertion of a properly mated key into the barrel or plug to unlock the latter.

Fig. 2 is a view similar to Fig. 1 illustrating the mating key within the plug and the knob lowered and interlocked with the key.

Fig. 3 is a reduced front view of Fig. 1.

Fig. 3A is a view on the line 3A—3A of Fig. 3.

Fig. 4 is a view similar to Fig. 3 showing the knob or closure depressed and concentrically disposed relative to the rotatable plug.

Fig. 4A is a sectional view on the line 4A—4A of Fig. 4.

Fig. 5 illustrates a view similar to Fig. 3 but with the mating key inserted in the cylindrical plug.

Fig. 5A is a sectional view on the line 5A—5A of Fig. 5 but with the plug omitted.

Fig. 6 is a view similar to Fig. 5 but with the knob depressed and removably interlocked with the key.

Fig. 7 is a sectional view on the line 7—7 of Fig. 6.

Fig. 7A is a fragmentary view of the plug shown in Fig. 7, however, with the slidable knob omitted.

Fig. 8 is a side elevational view of a mating key.

Fig. 9 is a perspective view of the cylinder lock.

Fig. 10 is a view taken on the line 10—10 of Fig. 1 to illustrate stop means for the slidable knob.

Fig. 11 is a fragmentary view of Fig. 2 however showing a slightly modified mating key removably concealed and interlocked by the slidably guided knob, and

Fig. 12 is a sectional view on the line 12—12 of Fig. 11.

Illustrative of the embodiment disclosed, the cylinder lock is generally designated CL and is characterized by a housing or casing C having a 50 longitudinally disposed cylindrical bore 10 for rotatably guiding the cylindrical plug or barrel P. The housing C is provided with spaced vertical and cylindrical bores 11 for slidably guiding the cylindrical driving pins 12 normally urged 55 24 are completely within the limits of the plug

downwardly by the helicoidal springs 13 appropriately retained within the casing C.

Cylindrical tubular pins 14 are slidably guided in the cylindrical bores 15 in the rotatable plug P and normally project into the key receiving longitudinally arranged slot 16 (Fig. 1). The tumbler pins 14 are of an unequal height and are adapted as is well understood to be actuated by properly cut shank S of a mated paracentric key K.

With the key K removed from slot 16 of the plug, the driver pins 12 are in part disposed within the bores 15 and consequently the plug is retained against rotation.

Where the key is fully inserted into the plug the tumbler and driver pins properly line up (Fig. 2) to permit rotation of the plug relative to the cylinder.

Associated with the plug and accessible at the front thereof is the slidably guided latching member or knob LM which is provided with a circular head H of a size coextensive with the size of the circular front face 18 of the plug which embodies a dovetailed reentrant and diametrically disposed recess broadly denoted 19 (Figs. 7, 7A and 9) having the rear vertical face 20 meeting with the forwardly extending inclined and converging and retaining faces 21 of the retaining lips or guide means 22.

Slidably guided by the inclined faces 21 is the forwardly extending dovetail shaped diametrically disposed boss 23 of the knob LM having the diverging lips or tracks 24 interlocked with and slidably cooperating with the retaining lips or tracks 22 of the plug P and with the spaced lips or tracks 25 defining with the rear face 26 in the front or anterior part of the casing C a vertically disposed reentrant and dovetailed recess 26' (Fig. 5A), the guide lips 25 defining the forwardly projecting and converging retaining faces 29 of the track means 25.

Knob LM is interrupted by a slot or recess 27 adapted to removably receive and house at least the proximal or front part 28 of the shank S of the key. This knob is also provided with the forwardly projecting boss 30 having the diametrically arranged slot 31 defined in part by the forwardly projecting wings or lugs 34 adapted to removably straddle and interlock with the rear part 32 of the bow B of the key K, part 32 of the bow B (Fig. 2) removably fitting into slot or gap 31 of the knob when the latter has been shifted downwardly and if shifted completely down, lips 24 are completely within the limits of the plug

and free of the spaced track means or lips 25 of the casing, the slots 27 and 31 at all times being oppositely disposed in respect to common web 33 of the knob as illustrated.

The plug P is automatically unlocked from the casing C when the lips or projecting means 24 of the knob LM strike the lower curved part 35 adjacent the bore 36 of the casing C and this bore forms the bearing for the enlarged cylindrical head 37 of the rotatable plug. Part 35 may thus be considered as stop means for the slidably guided knob or closure LM (Figs. 2 and 4). In Fig. 4 the knob LM is unlocked from the casing and against the stop portion 35 of the bore 36, that is, the knob serves as a closure to render keyway 16 inaccessible. By applying a finger thrust on the knob LM the latter may be slidably raised from the position indicated in Fig. 4 to its highest elevation shown in Fig. 3 at which time the knob still locks the plug against rotation.

Of importance is the coaction of the lips 24 of the knob with the curved portions or elbows 37 of the crown or upper portion 38 of the recess 26'. These curved portions 37 form a contracted part of recess 26' to preclude complete withdrawal of these lips 24 from the rotatable plug P when the latter is fully raised. Hence in the fully raised position of the knob, the latter is therefore still interlocked with the plug (note Fig. 1) wherein lips 22 of the plug are still interlocked with lips 24 of the knob, nevertheless keyway 16 is rendered fully accessible to allow for insertion of the key (Figs. 1, 3 and 9). Consequently even if a picking tool (not shown) be inserted in the keyway to actuate the tumbler pins 14 from the position shown in Fig. 1 to that illustrated in Fig. 2, the plug P still could not be turned for effectively revolving the conventional tail piece T carried by the plug because the knob LM at all times is interlocked with the plug and the only time that the plug may be turned or rotated is when the key is fully inserted into the keyway 16 (Figs. 2 and 10) and the latching member or knob LM is shifted completely downwardly for fully interlocking with the key.

For automatically holding the knob in a lowered or raised position, spheroidal antifriction means 40 backed up by a helicoidal spring 41 is confined in a socket or bore 42, the ball or antifriction means being constantly urged against the rectilinear walls or faces 28 and 26 of the aligned recesses 19 and 26' of the plug P and cylinder C respectively, when the knob is shifted to open or close the keyway 16. By this arrangement the knob may be held automatically even in a partly raised or lowered position.

Following the insertion of the key in the plug (Fig. 5), the knob LM is shifted downwardly against the resistance of the braking means defined by the ball 40 and spring 41 to the position shown in Fig. 6, thus unlocking the knob from the casing C. On downward displacement of the knob, portion 28 of the key is straddled by the spaced walls of the recess or slot 27 and portion 32 of the bow B is straddled by spaced lugs 34, that is, the key is now removably interlocked with the knob at a time when the latter is unlocked from the casing and at a time when the tumbler and driver pins 12 and 14 are lined up as illustrated in Fig. 2. Now by rotating the key 70 the plug may be desirably revolved to appropriately rotate the tail piece T as required. Following such operation, the knob may again be slidably raised to be free of the key, permitting withdrawal of the key removal from the plug. Pur- 75

suant to such removal the knob is lowered close to the keyway 16.

In Fig. 11, the key K' has no bow as B of the type shown in Figs. 2 and 8. Instead the front portion 28' thereof is provided with finger receiving grooves 29'. When the knob is fully raised, the walls of recess 27 completely clear the key K' permitting the removal thereof from the plug. With the knob fully raised the key may be also fully inserted into the keyway, and thereafter the knob is fully lowered whereby the front portion 28' is disposed within recess 27 and removably interlocked with the walls thereof. In other aspects the form illustrated in Fig. 11 is along the lines shown in Figs. 1-10.

In all of the embodiments disclosed with the key inserted into the key receiving slot or keyway 16 and with the latching means or knob LM fully depressed and interlocked with the key, the plug 20 of course may be rotated relative to the casing to actuate or revolve the tail piece T. This may be accomplished by grasping and rotating the spaced wings or lugs 34 which constitute manipulatable means.

25 The key can only be removed from the plug upon shifting the latching means or knob LM to its uppermost position in which instance the key is unlocked from the latching means and can readily now be withdrawn from the plug but even 30 at such times as previously pointed out the latching means is still interlocked with the plug and even though the tumblers 14 thereof may be tampered with the cylinder is pickproof as it cannot be revolved except by the use of its mating or 35 duplicate key.

Various changes may be made in details of construction and arrangement of parts without departing from the spirit of the invention or sacrificing any of the advantages thereof inherent 40 therein.

I claim:

1. A cylinder lock adapted to be unlocked by a key, comprising; a casing having an anterior portion embodying track means, a plug provided with a slot for receiving said key and rotatably disposed within said casing and having guide means, latching means accessible at the front part of said plug and casing and having rearwardly disposed projecting means slidably guided by and interlocking with said track means and guide means to preclude rotation of said plug relative to said casing, and means to limit displacement of said latching means in a direction away from said plug to render said slot accessible for insertion of said key therein at which time said projecting means is still interlocked with said guide means and track means.

2. A cylinder lock adapted to be unlocked by a key, comprising; a casing having an anterior portion embodying spaced track means, a plug provided with a slot for receiving said key and rotatably disposed within said casing and having spaced guide means, latching means accessible at the front part of said plug and casing and having rearwardly disposed and spaced projecting means slidably guided by and interlocking with said track means and guide means to preclude rotation of said plug relative to said casing, and means to limit displacement of said latching means in a direction away from said plug to render said slot accessible for insertion of said key therein at which time said projecting means are still interlocked with said guide means and track means.

3. A cylinder lock adapted to be unlocked by a

key, comprising; a casing having an anterior portion embodying a reentrant recess bounded by spaced track means, a plug provided with a slot for receiving said key and rotatably disposed within said casing and having a reentrant recess bounded by spaced guide means, latching means accessible at the front part of said plug and casing and having rearwardly disposed and spaced projecting lips slidably guided by and interlocking with said track means and guide means to preclude rotation of said plug relative to said casing, and means to limit displacement of said latching means in a direction away from said plug to render said slot accessible for insertion of said key therein at which time said projecting means are still interlocked with said guide means and track means.

4. A cylinder lock adapted to be unlocked by a key, comprising; a casing having anterior portion embodying track means, a plug provided with a slot for receiving said key and rotatably disposed within said casing and having guide means, latching means accessible at the front part of said plug and casing and having rearwardly disposed projecting means slidably guided by and interlocking with said track means and said guide means to preclude rotation of said plug relative to said casing, means to limit displacement of said latching means in a direction away from said plug to render said slot accessible for insertion of said key therein at which time said projecting means is still interlocked with said guide means and track means, and spring controlled braking means to resist displacement of said latching means relative to said plug.

5. A cylinder lock adapted to be unlocked by a key, comprising; a casing having an anterior portion embodying track means, a plug provided with a slot for receiving said key and rotatably disposed within said casing and having guide means, latching means accessible at the front part of said plug and casing and having rearwardly disposed projecting means slidably guided by and interlocking with said track means and guide means to preclude rotation of said plug relative to said casing, and means to limit displacement of said latching means in a direction towards said plug to render said slot inaccessible at which time said projecting means is unlocked from said track means but interlocked with said guide means to permit rotation of said plug relative to said casing if said key be disposed in said slot.

6. A cylinder lock adapted to be unlocked by a key, comprising; a casing having an anterior portion embodying spaced track means, a plug provided with a slot for receiving said key and rotatably disposed within said casing and having spaced guide means, latching means accessible at the front part of said plug and casing and having rearwardly disposed and spaced projecting means slidably guided by and interlocking with said track means and guide means to preclude rotation of said plug relative to said casing, and means to limit displacement of said latching means in a direction towards said plug to render said slot inaccessible at which time said projecting means are unlocked from said track means but interlocked with said guide means to permit rotation of said plug relative to said casing if said key be disposed in said slot.

7. A cylinder lock adapted to be unlocked by a key, comprising; a casing having an anterior portion embodying track means, a plug provided with a slot for receiving said key and rotatably dis-

posed within said casing and having guide means, latching means accessible at the front part of said plug and casing and having rearwardly disposed projecting means slidably guided by and interlocking with said track means and guide means to preclude rotation of said plug relative to said casing, means to limit displacement of said latching means in a direction towards said plug to render said slot inaccessible at which time said projecting means is unlocked from said track means but interlocked with said guide means to permit rotation of said plug relative to said casing if said key be disposed in said slot, and spring controlled braking means to resist displacement of said latching means relative to said plug or casing.

8. A cylinder lock adapted to be unlocked by a key, comprising; a casing having an anterior portion embodying track means, a plug provided with a slot for receiving said key and rotatably disposed within said casing and having guide means, latching means accessible at the front part of said plug and casing and having a rearwardly disposed hollow boss for removably interlocking with said key upon displacement of said latching means towards said plug and provided with spaced lips slidably guided by and interlocking with said track means and guide means to preclude rotation of said plug relative to said casing, means to limit displacement of said latching means in a direction towards said plug to render said slot inaccessible at which time said lips are unlocked from said track means but interlocked with said guide means to permit rotation of said plug relative to said casing if said key be disposed in said slot, and manipulatable means carried by said latching means.

9. A cylinder lock adapted to be unlocked by a key having a shank and a bow, comprising; a casing having an anterior portion embodying track means, a plug provided with a slot for receiving said key and rotatably disposed within said casing and having guide means, latching means accessible at the front part of said plug and casing and having a rearwardly disposed hollow boss for removably interlocking with said shank and provided with spaced lips slidably guided by and interlocking with said track means and guide means to preclude rotation of said plug relative to said casing, spaced wings carried by said latching member for removably interlocking with said bow, and means to limit displacement of said latching means in a direction towards said plug to render said slot inaccessible at which time said lips are unlocked from said track means but interlocked with said guide means to permit rotation of said plug relative to said casing if said key be disposed in said slot.

10. A cylinder lock adapted to be unlocked by a key, comprising; a casing having track means, a plug provided with a slot for receiving said key and rotatably disposed within said casing and having guide means, latching means having projecting means slidably guided by and interlocking with said track means and guide means to preclude rotation of said plug relative to said casing, and means to limit displacement of said latching means in a direction away from said plug to render said slot accessible for insertion of said key therein at which time said projecting means is still interlocked with said guide means and track means.

11. A cylinder lock adapted to be unlocked by a key, comprising; a casing having track means,

a plug provided with a slot for receiving said key and rotatably disposed within said casing and having guide means, shiftable latching means having rearwardly disposed projecting means slidably guided by and interlocking with said track means and guide means to preclude rotation of said plug relative to said casing, and stop means to limit displacement of said latch means in a direction away from said plug to render said slot accessible for insertion of said key therein at which time said projecting means is still interlocked with said guide means and track means.
